Des. 241,947

Patented Oct. 19, 1976

241,947

ELECTRICAL OUTLET BOX

William Maier, Bridgeport, Conn.
(125 Lawlor Terrace, Stratford, Conn. 06497)

Filed May 9, 1975, Ser. No. 576,211

Term of patent 14 years

Int. Cl. D13—03

U.S. Cl. D26—5 B

FIG. 1

FIG. 3

FIG. 2

FIG. 4

FIG. 5

FIG. 6

FIG. 8

FIG. 7

FIG. 1 is a perspective view of an electrical outlet box showing my new design;

FIG. 2 is a top view thereof;

FIG. 3 is a front view thereof;

FIG. 4 is a rear view thereof;

FIG. 5 is a right side view thereof;

FIG. 6 is a bottom view thereof;

FIG. 7 is a cross-sectional view taken on line 7—7 of FIG. 2;

FIG. 8 is an exploded view thereof.

I claim:

The ornamental design for an electrical outlet box, as shown.
